UNITED STATES PATENT OFFICE

96,085

DESIGN FOR A SHOE

Albert F. Bancroft, Newton, Mass., assignor to
Bancroft Walker Co., Waltham, Mass., a cor-
poration of Massachusetts

Application May 22, 1935, Serial No. 56,956

Term of patent 3½ years

To all whom it may concern:

Be it known that I, Albert F. Bancroft, a citizen of the United States, residing at Newton, in the county of Middlesex and Commonwealth of Massachusetts, have invented a new, original, and ornamental Design for a Shoe, of which the following is a specification, reference being had to the accompanying drawing, forming a part thereof, in which

Fig. 1 is a view in elevation of a left shoe showing my new design as seen from the outer side of the shoe, the outline of the heel being conventional and shown in dot and dash lines; and

Fig. 2 is a similar view showing the design as seen from the other or inner side of the shoe.

The ornamental effect of my design is char-

acterized by the dissimilar appearance of the two sides of the shoe, the inside shank side having a seam and merging into a wide strap having a line of perforation and ornament extending into it, and the other or outer side of the shoe being seamless, having lines of perforation and ornament converging to a large button which is received in the end of the cross strap, the cross strap converging in a pronounced manner to a narrow end.

I claim:

The ornamental design for a shoe substantially as shown and described.

In witness whereof, I have affixed my signature hereto.

ALBERT F. BANCROFT.
